DESIGN FOR A BISEAT AIRCRAFT CHAIR

Lewis C. McCarty, Jr., Towson, and Drew M. Helwig, Baltimore, Md., assignors to The Glenn L. Martin Company, Baltimore, Md.

Application August 18, 1934, Serial No. 52,989

Term of patent 7 years

To all whom it may concern:

Be it known that we, Lewis C. McCarty, Jr., and Drew M. Helwig, citizens of the United States, and residents respectively of Towson in the county of Baltimore and State of Maryland, and of Baltimore, in the State of Maryland, have invented a new, original, and ornamental Design for the Biseat Aircraft Chair, of which the following is a specification, reference being had to the accompanying drawing, forming part thereof.

The drawing figure is a front perspective view

of the subject chair, showing the ornamental structure in common with the bracing, sectionally upholstered sling seats and backs, safety belts, and one of the chair backs adjusted for a reclining person.

We claim:

The ornamental design for a biseat aircraft chair substantially as shown and described.

LEWIS C. McCARTY, JR.
DREW M. HELWIG.
